UNITED STATES PATENT OFFICE.

RAYMOND D. SMITH, OF EAST MILTON, MASSACHUSETTS, ASSIGNOR, BY MESNE ASSIGNMENTS, TO HOWARD TIME APPLIANCE CO., OF ROXBURY, MASSACHUSETTS, A CORPORATION OF MASSACHUSETTS.

ELECTRIC-SWITCH RESPONSE TIMER.

Application filed December 15, 1917, Serial No. 207,303. Renewed March 22, 1923.

To all whom it may concern:

Be it known that I, RAYMOND D. SMITH, a citizen of the United States, residing at East Milton, in the county of Suffolk and 5 Commonwealth of Massachusetts, have invented a new and Improved Electric-Switch Response Timer, of which the following specification, in connection with the accompanying drawings, constitutes a full and 10 clear description.

This invention relates in general to timing mechanism for governing automatic actuation of electric switches or the like; and particularly concerns timer mechanism 15 of the type arranged normally to be inactive and to permit the switch to be opened or closed by hand manipulation in the ordinary way except when it is desired to avail of the timer function, which, in the present 20 instance, is to interpose a delay interval of predetermined duration between the usual hand manipulation of the switch control means and the operative, circuit-controlling throw of the switch responsive to such manipulation.

In such timer mechanism it is preferable 30 that the clock spring be wound by the action of setting the time instead of requiring the use of a separate winding key or the like as is the common practice in most 35 time switches in common use. Also in timer mechanisms of this type it contributes greatly to the simplicity and convenience of operation that the timer be capable at all 40 times of being set for switch controlling action irrespective of whether the switch is in circuit-making or circuit-breaking position. This is one of the advantages attained in my improved response timer.

45 A common source of unreliable and unsatisfactory operation in so-called time-switches of the type which incorporate a time-keeping mechanism designed to run for a week or longer at one winding of the clock spring is that near the end of this period as the clock spring becomes "run down" and its power depleted, the clock inclines to slow up and lose time or even 50 stop entirely unless kept in perfect condition by frequent cleaning and oiling, which is impracticable in every day service. This trouble is augmented by the common practice in time switch construction of adding to the duties of the clock spring some me-

chanical function such as to trip escapement 55 mechanism, for actuating the switch or in some cases the main spring of the clock is even called upon to produce the power which does work equivalent to hand manipulation of the switch. It is obvious 60 that any error, in accurate time keeping induced by the above burdens in a clock which runs for a week or more at one winding is accumulative in nature and after several 65 days of operation may result in the circuit being turned "off" and "on" at very different times than intended.

In contrast to so-called "time switches" 70 constructed and operating on the above principles, I prefer to term my improved time switch a "response timer" which indicates, as above described, that the clock mechanism is designed to run only during that period between hand tensioning of the 75 switch and the responsive time-controlled switch action, whereby any error in accurate time keeping can not accumulate to a troublesome degree and whereby the dependability of the service given by the clock mechanism is greatly increased, owing 80 partly to the fact that the main spring of the clock never "runs down" beyond a designed point, and exerts at all times during its operation, sufficient driving power to overcome the bad effects of congealed oil, 85 dirt accumulation, or other handicaps to clock operation and accurate timing.

I arrange the timing mechanism in my improved response timer to be operatively de-energized and idle until manually energized and set in operation for the purpose 90 of controlling automatic action of the switch, and by designing the switch to be tensioned by hand each time it is to be used as a time switch I am required to provide 95 the switch with no motive power to effect its automatic action other than a spring connection between its operating handle or button and the contacts, similar to that commonly employed for causing the snap action 100 in various forms of snap switch mechanisms.

From the above it will have become apparent that all power means employed (conveniently in the form of springs) are designed to be energized for operation only at 105 the express time of availling of same for delaying circuit-breaking response of the switch to the manual actuation of the

switch operating handle. In practising one form of my invention, I employ two separate control handles or the like, one, preferably of conventional form, as mentioned above, for operating (and also for tensioning) the switch, and another for energizing and setting in operation the timer mechanism. Whereas in another form of my invention, I may advantageously connect the timer mechanism to be energized and set in operation by the same movement of the switch operating handle that tensions the switch for delayed automatic action. In this latter arrangement, there is obviously no use for a separate operating handle for the timing mechanism as above described, and I, therefore, may advantageously provide, in place of such separate operating handle, an adjustable, time-indicating pointer-hand, that through associated mechanism is adapted to vary, and to predetermine the operative extent of energization, and also the time setting of the timer as caused by the constant and full, switch-tensioning movement of the said operating handle.

This latter form of my invention contemplates, briefly, the provision of some conventional form of electric switch (as, for instance, a knife switch) that may be controlled by hand actuation in the manner of an ordinary, non-automatic switch, to govern a lighting or other load circuit, but possessing the additional feature in operation, that upon adjustment of an associated pointer-hand to establishment in other than its "zero" position, a time interval of the extent indicated by said pointer-hand, will be made automatically to intervene, at each operation, between the usual actuation of the switch control handle for opening the switch, and the actual tension caused opening of the switch responsive to such actuation.

Preferred embodiments of my invention are illustrated in the accompanying drawings wherein:

Fig. 1 is a front elevation of my simplified timer mechanism as applied for illustrative purposes, only, to a conventional type of two-blade, knife switch,—the switch panel being shown as broken away to expose certain of the timer parts.

Fig. 2 is a view looking at the right of Figure 1, with the casing partially broken away to show the timer retarding train, certain parts being sectioned more clearly to show their construction.

Fig. 3 is a partial plan view showing certain of the detent parts for controlling movement of the switch blades.

Fig. 4 shows in front elevation a modified form of my improved timer mechanism as applied to a similar type of two-blade knife switch, the switch structure being omitted

in this figure better to show the parts back of the panel.

Fig. 5 shows in right elevation, and partially in central section, the complete switch and timer mechanism in its said modified form.

Fig. 6 is a vertical section through a part of the timer operating mechanism taken on the vertical plane 6—6 in Fig. 5, looking in the direction of the arrows.

Fig. 7 is a plan view taken in section on the horizontal planes 7—7 in Fig. 5.

Fig. 8 is a sectional view similar to Fig. 6 but showing the parts positioned to accord with Fig. 5, together with more of the associated mechanism.

Fig. 9 is largely diagrammatic and shows a still different operative position of the parts in Fig. 6.

Fig. 10, also diagrammatic, indicates these same parts in their normal or ordinary position.

Fig. 11 is a sectional view on the plane 11—11 in Fig. 5.

Each part bears the same reference number when appearing in different figures of the drawings and will be designated thereby in the following description.

In Figs. 1 and 2, binding posts for the circuit lead wires 2 appear at 3. The conductive blades 4 of usual construction are friction-pivoted respectively in lower terminal hinge clips 5 mounted on a vertical support panel 6, of slate or other suitable insulating material, so as to swing into and out of switch-closing engagement with upper terminal clips 7. A brace bar 8 of insulating material bridges these blades at their tops, but in place of the usual control handle for operating the blades, this brace bar carries a bracket mounting 9 for a detent catch finger 11 pivoted at 12 and urged by a spring 13 to a position as shown in Fig. 2, wherein a lower portion 14 of said finger abuts against the brace bar 8, and an upper portion 15 extends upwardly to a position for interceptive engagement with a detent 16 carried between, and at the extremities of, the double armed detent lever 18, which is pivoted at 19 to a bracket 20 mounted on the top edge of the support panel 6.

The usual switch control handle 22 is fixedly carried by a separately pivoted, actuating structure comprising a two-legged upright swinging arm 23 that in turn is carried rigidly by, and as part of, the horizontal straddle-bar 24, each end of the latter being pivoted at 25 to bracket terminals 26 extending forwardly from either side of the panel base. The entire actuating structure above described will hereinafter be referred to as the actuator.

A powerful, coiled, extension spring 27 connects an anchorage projection 28 of the actuator and a corresponding anchorage pro-

jection 29 of the blade structure, this spring normally acting to hold the actuator and the blade structure together as shown in Fig. 2, where buffer lugs 30 formed as extensions of the bracket 9 are shown as seated in spring buffer clips 31 carried by the actuator for shock-absorptive purposes herein-after to be explained.

It should be noted that the angle made by 10 the forward engaging edge 32 of catch finger 11 relative to the path of travel of detent 16 as carried by detent lever 18 is such as to exert pressure on this detent in a direction that will tend to displace said 15 detent upwardly and out of the path of said finger to permit switch-opening movement of the blade structure whenever the detent lever 18 is free to yield. On the other hand, this angle is not such as to set up reactive 20 pressure on the pivoted catch finger 11 in a direction to cause the latter to yield downwardly to permit such switch-opening movement of the blade structure; although it will be evident from inspection of the mechanical 25 relation of parts, as shown in Fig. 2, that movement of the blade structure to close the switch will always be permitted freely by such downward yielding of the catch finger whenever the detent arm 18 is locked against 30 upward yielding movement.

It is thus apparent that the blade structure is normally free to be moved to and from its switch-closing position, and that to lock the same therein, it is necessary merely 35 to prevent upward yielding movement of the detent lever 18. To block, and at a predetermined time thereafter to release, this detent arm (respectively to prevent and to permit such yielding movement thereof) is 40 the office of the simple timer mechanism hereinafter to be described.

When the detent arm 18 is blocked against yielding, swinging displacement of the actuator to its broken line position shown in Fig. 45 2 will obviously separate the actuator from the blade structure and tension the connecting spring 30. To establish the parts thus tensioned, a locking strut arm 34 is friction-pivoted at 35 to the actuator structure, said 50 arm at its free end riding through an opening 36 in the panel 6 and being guided therein by a check pin 37 that horizontally spans said opening and passes through a longitudinal slot 38 in said strut arm. A notch 39 at 55 the far end of this slot is adapted to engage with the check pin to hold the actuator in its broken-line position in Fig. 2. The strut arm 34 may, however, at any time be disengaged from the check pin 37 by pressing 60 downwardly with the thumb on a plunger trip rod 40 that passes centrally through the handle and at its lower end is bent to extend through, and to be guided in, an elongated slot 42 in the side of the actuator structure, 65 thereby to engage with a tripping extension

43 of the strut arm. A plunger spring 44 normally acts to hold the plunger rod 40 in its uppermost position.

It remains to describe the simple timer mechanism before referred to, whereby the 70 detent lever 18 is controlled. This is contained, for the most part, in a closed chamber within a metallic mounting box 45 back of the panel 6. Pivoted at 46 to the rear face of the support panel 6 is a bell crank lever comprising a short arm 47 that extends horizontally to the left from said pivot, as shown in broken lines, Fig. 1, and terminates in a shelf-lug 48 directly beneath and engaging the lower end of a universal presser coupling 50, that at its upper end similarly engages with a rearward extension 51 of the detent lever 18 to receive presser impulses therefrom. The other, and longer, or feeler arm 52 of this bell crank lever is angular and extends obliquely downwardly terminating in a rearwardly turned end 53. Mounted for rotation adjacent to this lower end of feeler arm 52, is a timer cam 55 normally so positioned rotatively that a notch 56 in the periphery thereof registers with said end 53 of the arm 52 to permit the movement thereof radially inwardly of the cam, as would obviously be caused by the upward yielding of detent arm 18 heretofore mentioned. A 95

light spring 57 however acts yieldingly to hold the said end of feeler arm 52 out of said notch and to retain lever 18 against stops 17 and the detent 16 in its lower position for engagement with catch finger 11. The tendency of finger 11 to displace detent 16 from its path, however, is of such relative magnitude as to overcome the action of spring 57. Obviously, therefore, when the notch 56 in cam 55 registers with the end of feeler arm 52 yielding of the detent lever to release the blade structure for switch opening will be permitted by entrance of arm 52 into this notch. But if this notch 56, as shown in full lines in Fig. 1, is displaced from such registering position, yielding of the detent lever 18 will be positively blocked by engagement of feeler arm 52 with the periphery of the cam. 100

Cam 55 is fixedly mounted on the main 115 and winding spindle 58 of a simple, self-contained escapement retarded time movement shown most fully in Fig. 2. Mounted for independent rotation on the same spindle is a large retarding gear 59 that is in mesh with a train of smaller retarding gears not designated by number because well known in structure and function to those skilled in the art. Power for driving this retarding train and for simultaneously rotating cam 55 in one direction is had by storing tension in the band spring 60. This spring at one end is connected to the winding spindle 58 and at the other end 62 to a frame stud 63. The spindle 58 has bearings in front and rear 120 125 130

frame plates 64, 64 of the timing movement and passes through the bushing 65 in the support panel 6 extending forwardly through the latter and fixedly carrying in front thereof 5 of a combined winding and time-indicating pointer-hand 66 provided with operating handles 67.

The total rotative movement of the main spindle 58 and of the cam 55, fixed thereon, 10 is limited approximately to one complete turn by a stop pin 69 that projects forwardly into the path of pointer-hand 66 from the face of a graduated dial 70 mounted on the front of the support panel 6. The band 15 spring 60 always tends to rotate the cam 55 and pointer-hand 66 clockwise to their stop limited position indicated by broken lines in Fig. 1. In this position of parts, the peripheral notch 56 in the cam 55 is positioned 20 as also indicated in broken lines to register with the end of feeler arm 52.

To set the normally idle and de-energized timer movement for operation, the pointer-hand 66 is turned counter-clockwise in Fig. 25 1 by means of its handles 67 to some desired time setting, such as shown by full lines in Fig. 1, and is then released. This actuation will wind the spring 60 but will not actuate the retarding train because a ratchet wheel 30 71, that is friction mounted against a shoulder on the spindle 58 through the axially exerted tension in spring 61, will slip under the retarding pawl 72 carried on the side of the large retarding gear 59 in well known manner. The band spring 60 obviously will be wound to an extent proportional to the rotating displacement of pointer-hand 66 from its "zero" position, and will be unwound as it returns said hand to such position. Slow return of the pointer-hand and cam results from the retarding action of the gear train as transmitted to the spindle 58 through the friction hold thereon of ratchet wheel 71, such action consuming an interval 40 of time proportional to the degree of displacement of pointer-hand 66 from its zero position. Or, if desired, the winding spindle 58, together with cam 55 and time pointer 56 fast thereto, may be returned directly 45 to "zero" position independently of the retarding train by turning the pointer 56 and winding spindle 58 in clockwise direction with sufficient strength to overcome the friction hold between ratchet wheel 71 and spindle 58, thus forcing a slippage between these two members which the spring 60, alone, is not powerful enough to effect.

From the foregoing, it will be clear that when the timer parts are normally de-60 energized and positioned as shown in broken lines, Fig. 1, the blade structure of the switch will swing in unison with the actuator directly to open or close the switch in the usual manner. When, however, it be 65 desired to interpose a period of delay be-

tween actuation of the control handle 22, and actual responsive opening of the switch to break a circuit, say, for extinguishing the lights, the pointer-hand 66 is first turned to the left to any selected setting, then released, after which the actuator is swung to its locked position shown in broken lines in Fig. 2 against the tension in spring 27,—corresponding movement of the blade structure being prevented by the cam-locked 70 detent 16. Spring 27 upon timed return of pointer-hand 66 to its zero position and of notch 56 in cam 55 to its position for registering with the end feeler arm 52, will then cause a quick, follow-up movement of the 75 blade structure to open the switch. As the impact between the blade structure and the actuator is considerable, the buffer lugs 30 and clips 31, or other suitable devices may be employed to absorb the shock. 80

It will be observed that this time setting may be effected regardless of whether the switch is in circuit-making or circuit-breaking position and that the switch may be closed independently of time control even 90 after the timer has been set for action, thus restricting the respective controls of the timer and switch to no definite sequence or combined manner of operation which greatly simplifies and renders more convenient 95 their use.

The above described structure, however, accomplishes only a part of the objects of my present invention as set forth at the beginning of this specification. It may be 100 desired, for convenience, to concentrate all actuating control of the switch, including the timed automatic government thereof, in the single switch operating handle 22. Obviously to do this, connections must be provided, whereby at some time in its movements, said handle will not only tension the blade structure to effect automatic switch opening, but will also energize and release for operative return of cam 55, the normally 105 idle timer movement hereinbefore described as designed for independent actuation by a separate control handle. Such provision appears in the modified form of my improved response-timer appearing in Figures 110 4 to 11 of the drawings.

Referring, now, to these figures, I may provide as means for winding and releasing the timer movement through a constant, 115 blade tensioning, stroke of the actuator, a system of gearing that may receive operating impulse from a gear segment, such as shown at 74. This gear segment is carried at the rear end of a spoke arm 75 that is formed to extend through a lateral opening 120 76 in the wall of the timer compartment, and is carried as a fixed part of the actuator straddle bar 24, thereby to swing in fixed 125 relation to the actuator about the latter's pivot. 130

In a rear corner of the timer compartment, I may conveniently mount, by means of screw studs, 77, 77, an angle-plate rack 78 having teeth on each of its longitudinal edges and being constrained for vertical movement by a long slot 79 in one of its sides that engages with said screw studs.

This rack at one of its toothed edges is positively enmeshed with segment 74 always 10 to slide up and down correspondingly to swinging movement of the actuator, and at its other toothed edge engages an idler gear 80 rotating on a fixed stud 82 that is mounted in the rear wall of the timer box 45. This 15 idler gear is in turn enmeshed with a pinion 83 rotatably mounted on a similar fixed stud 84. The latter stud, however, is co-axial with the winding spindle 58 of the timer movement although structurally separate there- 20 from.

As shown in Fig. 11, the pinion 83 is fixed to a common hub 87 with a winding disc 85 although between said pinion and disc, a timer gear 86 of greater diameter 25 is also mounted freely to turn on, and relative to, said hub for purposes later to be explained. The ratio of gearing is such that a full swinging stroke of actuator in its direction to open the switch rotates the 30 winding disc 85 substantially one complete turn in a counter-clockwise direction, Figs. 4, 6, 8, 9 and 10.

Also mounted on stud 84, and adjacent to hub 87, is an escapement disc 90 35 having a bearing hub 89 and that carries two forwardly projecting prongs 91, engaging at diametrically opposite points, with corresponding openings in a winding plate 95 that is fixedly carried on the main winding spindle 58, Figs. 5 and 7. The escapement disc 90 is also freely rotatable on stud 84 and has connection with the winding disc 85 only through releasable engagement in one direction between a cam lug 93 carried 40 on the winding disc 85 and a tripable latch 94 carried on the opposing face of the escapement disc 90. This latch is normally positioned by a light spring 96 against a stop pin 97 carried on the escapement disc 50 as shown in Figs. 6 and 9 but may yield to the opposite limit of its swing as determined by another pin 98 also carried on the escapement disc 90 as shown in Figs. 8 and 10. When in its normal position, the rearwardly 55 turned end 99 of latch 94 is adapted to be engaged by an edge 100 of the cam lug 93, these parts, however, being capable of interference at no other points.

The timer movement is structurally and 60 operatively the same as described in reference to Figs. 1, 2 and 3, with the exception that the time-setting pointer-hand 66 is no longer carried by winding spindle 58.

The timer setting gear 86, heretofore mentioned carries on its forward face a trip

pin 102 extending into the path of a projecting portion 103 of the latch 94, which extends forwardly beyond the periphery of escapement disc 90. Two idler pinions 104 afford gearing connection of said timer setting gear 86 with a similar gear 105 fixedly carried on an arbor 106 that has a bearing 65 in the support panel 6, and carries directly in front of the latter the pointer-hand 66 with the usual handles 67, 67, and a co-operating time indication dial 70 similar in every respect with these parts as they appear in the form of my invention shown in Figures 1 to 3. This pointer-hand now, however, has no direct connection with the timer cam 55 or the spindle 58 but is held established and stationary in such position as it may be desired to adjust the same, by the detent plunger ball 107, adapted to seat in openings 108 circularly arranged in the gear 85 10. Obviously, the rotative position of the pointer-hand bears a constant relation to the rotative position of trip pin 102, and by means of the handles 67, 67, such rotative position may be varied at will. 90

This modified form of my improved timer operates as follows.

The timer control parts are shown in their normal positions in Fig. 10. Here the pointer-hand 66 is supposed to be positioned at zero, and the actuator is in its broken line position indicated in Fig. 5. It will be seen that the trip pin 102 is holding outwardly the end 99 of latch 94 that normally is positioned to be engaged by the lug 93, and that the notch 56 in cam 55 registers with the end 53 of feeler arm 52, so that upon the switch-opening stroke of the actuator (and consequent rotation of the winding disc 85 in a counter-clockwise direction, Fig. 10) no engagement will occur between said lug 93 and latch 94. The timer cam 55 and timer movement will remain, therefore, undisturbed permitting the detent roller 16 to yield upwardly and permit passage of catch finger 11, and movement of the blade structure to open the switch, in the usual manner. 100

Assuming now, that before such switch-opening stroke of the actuator, the pointer-hand 66 is displaced from its zero position, and the trip pin 102 thereby revolved counter-clockwise to some position such as shown in Fig. 9, then latch 94 will be urged by spring 96 into the path of lug 93, so that when the latter is moved with the winding disc 85 by said stroke of the actuator, the escapement disc 90 will be picked up and rotated in a direction to wind the band spring 60 of the timing movement. Such winding rotation of the escapement disc is, of course, accompanied by corresponding rotation of the main spindle 58 and timer cam 55, and continues during the said stroke of the actuator until pro-

jecting portion 103 of latch 94 is encountered by the trip pin 102. At this point the said latch will be disengaged from said lug and released for automatic timed return 5 under the stored-up power in band spring 60, in the usual manner,—the lug 93 continuing through its full revolution corresponding to a full stroke of the actuator after being thus relieved of the escapement 10 plate at the point predetermined by the setting of the trip pin 102.

In the operation above described, there are several features of operation that should be noted. One is that although lug 93 will 15 always pick up and carry the escapement disc 90 counter-clockwise to a point predetermined by the setting of trip pin 102, yet operative interference of said lug, with latch 94, when passing in the opposite direction, 20 is always prevented by the cam formation given to the lug 93 which causes natural yielding of latch 94, as shown in Fig. 6. Another point to be noted is that in order for the blade structure to be held in switch- 25 closing position and tensioned for timed release, the timer cam 55 must be moved to displace the notch 56 therein from registering position with the end of feeler arm 52, before the blade structure encounters the 30 detent roller 16. To provide for this, suitable operative lost motion, or back-lash, is arranged between the blade structure and the detent roller when the blade structure is fully seated in the terminal clips. But 35 in addition to this back-lash, introduced for the purpose just described, a purely idle lost motion of greater extent is desirable to insure that even though the blade structure is not pushed entirely back to its switch 40 closed seat, the cam lug 93 will always return rotatively to an extent sufficient to pass into engaging relation with the latch 94,—ready, as shown in Fig. 10, on subsequent switch-opening stroke of the actuator, to 45 wind up and set in operation the timing movement, in the manner before explained. To make allowance for this additional and purely idle back-lash, peripheral elongation of the notch 56 in cam 55 is provided. It 50 will be appreciated that the need of such idle lost motion is largely due to the fact that a small angular movement of the actuator results in a much greater angular movement of the timer cam. A positive 55 stop for the spring-driven timer movement is provided by a pin 110 that engages a spur 112 on the winding plate 95, Figs. 4 and 5, it being clear from the arrangement as shown in Figs. 8 and 10, that at any 60 time desired, direct return of these parts to their stopped, or normal, position to effect release of the blade structure or for other purpose, may be caused by turning the pointer-hand 66 in a clockwise direction 65 back to zero, which action will cause the

trip pin 102 to impel the escapement disc through engagement with latch 94, until these parts are returned to their positions as in Fig. 10, regardless of what position the cam lug 93, may at the time occupy. 70

Briefly reviewed, the operation of the further developed form of my invention above described is the same as that of the simpler form shown in Figs. 1 and 3, with the exception that the time indicating 75 pointer-hand is no longer carried by the movement spindle as an actuating and winding extension therefor. But such pointer constitutes merely an adjustment agent, that remains wherever stationed and, while 80 so stationed, operates automatically at every switch-opening operation to predetermine the period of delay automatically caused to intervene between movement of the actuator to its full line position in Fig. 5, and responsive, tension-caused, switch-opening movement of the blade structure, to break the circuit. 85

It will be appreciated that whereas, for 90 simplicity, I have chosen to disclose my improved timer arrangement as applied to an electric knife switch, the scope of the invention is by no means limited to such application. Thus I may as readily combine my improved and simplified timer arrangement, with switch structures of radically 95 different types, such as either rotary or push-button wall switches of standard and approved design; or my invention and especially the further developed form thereof 100 last described, wherein all actuating control is concentrated in common main control handle, is as readily embodiable in timer mechanism for a gas-valve or other device, as for electric switches. 105

My invention will be understood as not confined to the specific embodiments thereof herein disclosed, but what I claim as new is:

1. In an electric time switch, in combination; a movable circuit-governing member; resilient means tending when actively energized to cause operative movement of said member; a separately mounted detent movable to and from a position for intercepting said member to prevent said operative movement thereof and normally spring-urged into said position; and normally idle timing mechanism embodying a mechanically retarded timer element movable in operative relation to said detent, and a motor spring tending to impel said element to a definite stop-determined position out of operative relation to said detent, said spring being connected to be energized for action by the displacement of said element from its said position, and the said timing element being arranged during its spring-impelled travel to hold the detent in its 110 said position for intercepting said member. 115

120

125

130

2. In an electric time switch, the combination with a movable contact member; of resilient means for establishing tension tending to cause circuit-switching movement of said member; a movable detent positioned by resilient means in the path of said member and normally arranged to be thrust from said path by the pressure of said member thereon, thereby to permit said circuit-breaking movement; a locking element normally positioned to free said detent but adjustable to a position for preventing said detent from yielding to the thrust of said member; and timing mechanism adapted to 10 actuate said element, thereby to release said detent and permit its said yielding movement at a predetermined time.
3. In an electric switch, in combination; a movable contact member arranged to be 20 manually established in different circuit-controlling positions; power means tending when energized and rendered operative, automatically to impel said member to a definite circuit-controlling position thereof; a manually adjustable timer element, with separate power means operative when energized slowly to impel said element to a stop-determined position thereof; and a detent operatively related to said contact member and arranged to be controlled by movement of said element, thereby to time the operation of said first-mentioned power means;—the said member, element and detent being free from any fixed interconnection and so co-operatively arranged that said member and said element are normally free of operative restraint by one another, except when said element is displaced from its said stop-determined position.
4. In a timing mechanism for an electric switch, the combination with a circuit-governing switch member of an operating handle arranged to tension said member automatically to shift from one to another of its operative positions; a manually displaceable and self-restorable timer element normally idle in a definite stop-determined position wherein it is out of operative relation to said member; and interposed detent parts arranged to be rendered operative by displacement of said element from its stop-determined position to prevent tension-caused movement of said member for a limited interval of time but normally disposed to free both said member and said element for independent movement.
5. In timing mechanism for an electric switch, the combination with a circuit-governing switch member of an operating handle arranged to tension the latter automatically to shift from one to another of its operative circuit-controlling positions; a manually displaceable and self-restorable timer element normally idle in a definite stop-determined position wherein it is out of oper- 50 ative relation to said member; and an interposed detent movable into the path of said member to intercept the latter, said detent being normally out of engagement with said element but operably related thereto when the latter is displaced from its stop-determined position to be locked in the path of said member until restoration of said timer element to its stop-determined position.
6. In timing mechanism for an electric switch, the combination with a circuit-governing switch member of an operating handle to tension the latter automatically to shift from one to another of its operative circuit-controlling positions; a manually displaceable and self-restorable timer element normally idle in a designed stop-determined position wherein it is out of operative relation to said member; and an interposed detent movable into the path of said member to intercept the latter and formed co-operatively therewith to be displaced from said path by the engagement therewith of said member in passing,—the said detent being also operably related to said timer element when the latter is displaced from its said stop-determined position to be positively locked in the path of said member until restoration of said timer element to its stop-determined position.
7. In timing mechanism for an electric switch, the combination with a circuit-governing switch member of an operating handle to establish the said member in different circuit-controlling positions, and a movable relative to said member to a locked position to tension the same automatically to shift from one to another of its said positions; a manually displaceable and restoring timer element normally idle in a definite stop-determined position wherein it is out of operative relation to said member; and a separately mounted interposed detent movable into the path of said member to intercept the latter;—said detent being operably related to said element when the latter is displaced from its stop-determined position to be locked in the path of said member until self-restoration of said element to its stop-determined position.
8. A switch-action interval timer embodying, in combination; a spring operated switch mechanism having a control handle operable to actuate the switch contacts and also to tension them for automatic action; an escapement mechanism to govern said automatic action; and a spring driven timer mechanism operable to govern the said escapement mechanism and having a time indicating handle, movement of which in opposite directions acts respectively to energize and de-energize the driving spring of the timing mechanism.
9. In combination; an electric switch having a control handle and movable con-

tact governed thereby; a retarded, spring-driven timer normally held idle in a stop-determined position wherein it frees said contact for movement responsive to said handle, and means operated by said timer to restrain said contact when the timer is displaced from its stop-determined position, said means acting normally to permit free and independent movement of said timer to and from its stop-determined position.

10. In combination; an electric switch having a control handle and movable contact governed thereby; a retarded, spring-driven timer normally held idle in a stop-determined position, wherein it frees said contact for movement responsive to said handle, and means operated by said timer to restrain said contact when the timer is displaced from its stop-determined position; together with a time indicating handle for adjusting said timer to and away from its stop-determined position, and connections whereby movement of said time indicating handle in opposite directions respectively energizes and de-energizes the driving spring for said timer.

11. In combination; an electric switch having a control handle and a movable contact spring-connected thereto to be impelled thereby; a retarded, spring-driven timer normally held idle in a stop-determined position, and means normally conditioned to permit the displacement of said timer from its stop-determined position and rendered operative by said timer to prevent movement of the switch contact when the timer is so displaced; whereby movement of the switch control handle after said timer is so displaced, tensions the switch contact to perform an automatic movement under the control of said timer.

12. In timing mechanism for an electric switch, the combination with a circuit-governing switch member of an operating handle mounted for limited movement relative to said member and arranged to tension the latter automatically to shift from one to another of its operative circuit-controlling positions; a manually displaceable and self-restoring timer element normally idle in a definite stop-determined position wherein it is free of operative relation to said member; and an interposed detent movable into the path of said member to intercept the latter, the displacement of said element from its stop-determined position being permitted by said detent as normally conditioned and causing said detent to be locked in the path of said member for a pre-determined time.

13. A switch action interval timer embodying, in combination; a switch and mechanism for establishing tension tending to actuate the same, a timer, with associated detent means governed thereby for controlling tension caused actuation of the

switch, separate control handles for separately operating respectively said switch and said timer, to tension the switch for automatic action under control of the timer and so related when both handles are normally conditioned that each of said handles may be operated independently of the position of the other.

14. In an automatic switch, in combination; a control handle and a movable switch contact held in normal relative position by a connecting spring; two detents positionable respectively to retain said handle and said member when the latter are relatively displaced against the action of said spring; a timer operative on the detent controlling said member and at a predetermined time acting to free the latter for spring caused return to its normal position relative to said handle; the arrangement being such that the freeing of said member by its detent permits said handle to effect further switch controlling movement.

15. In a time switch in combination with a switch contact, a handle operable both to actuate said contact and to energize it for time controlled action; a timer; a handle separate from the first said handle and operable both to position said timer and to energize it for movement to control said contact; and detent parts adapted to hold said switch contact in designed position and later to release it under the control of said timer.

16. In a time switch in combination with a switch contact, a handle operable both to actuate said contact and to tension it for time controlled action; a timer; a handle separate from the first said handle and operable both to position said timer and to tension it for movement to control said contact; and detent parts adapted to hold said switch contact in designed position and later to release it under the control of said timer, said detent parts being normally conditioned to free both the said contact and said timer for separate and independent movement.

17. In combination; an electric switch having a control handle and movable contact governed thereby; a retarded, spring-driven timer normally held idle in a stop-determined position, wherein it frees said contact for movement responsive to said handle, and means operated by said timer to restrain said contact when the timer is displaced from its stop-determined position; together with a time indicating handle for adjusting said timer to and away from its stop-determined position, and connections whereby movement of said time indicating handle in one direction energizes the driving spring for said timer.

18. A switch action timer embodying in combination, a spring-actuated switch contact, means to tension said contact for quick action, mechanism to retain said contact

while tension is established in its actuating spring and subsequently to release said contact for quick tension-caused action, and a spring-driven timing movement operative upon said contact co-operatively with said mechanism and having a time indicator and winding handle, movement of which in opposite directions acts respectively to energize and de-energize the driving spring of the timing movement.

19. In combination, an electric switch having a contact controlled by spring and detent mechanism; a retarded spring driven timer normally held idle in a stop-determined position and operative upon said con-

tact co-operatively with said detent mechanism at a pre-determined time after said timer is displaced from its stop-determined position; together with a time-indicating handle for adjusting said timer to and away from its stop-determined position, and connections whereby movement of said time-indicating handle in one direction energizes the driving spring for said timer.

Signed at Boston, Massachusetts, this 13th 25 day of December, 1917.
